UNITED STATES PATENT OFFICE

DAVID SARASON, OF MUNICH, GERMANY

APPARATUS FOR THE EXTERNAL TREATMENT OF PARTS OF THE BODY BY WATER

Application filed October 22, 1928, Serial No. 314,215, and in Germany August 21, 1928.

This invention relates to an apparatus for the external treatment of parts of the body by water with the aid of a yieldable container, impermeable to water designed to be pressed on the part of the body to be treated. Such apparatus have hitherto been in the form of ice-bags and the like and they have an opening through which water or ice is admitted into the container, whereupon the bag has to be placed on the part of the body to be treated. Such ice-bags or water bottles present the inconveniences that if not filled sufficiently the wall bulges and comes into touch with the body on a comparatively small surface only specially on curved parts of the body. If such an apparatus has to be used for a longer time, it is much more practical to have a very great filling. The commonly used apparatus have to be secured in position by being wound around with bandages so that a very bulky packing is produced. When the water in the bag or bottle has to be renewed these bandages have to be removed this being troublesome and causing much loss of time.

All these inconveniences are avoided according to the invention by a bag of yieldable material impermeable to water and communicating with a water container adapted to be compressed. The water bag is applied on the body in the empty state and it can be easily filled subsequently from the water container. The soft waterbag adapts itself to any curve of the body, and means are provided for tightly applying the same onto the surface of the body even at and after the filling with water. On the inner surface of the apparatus designed to touch the body, an insert of absorbing material is provided which, if prior to the application it has been soaked in water, serves to make the water act directly onto the corresponding part of the body.

Another advantage of the invention consists in that the water can be withdrawn from the waterbag at any time and fresh water can be filled in without the necessity to detach the water bag.

Several embodiments of the invention are

illustrated, by way of example, in the accompanying drawing, in which

Fig. 1 shows a water bag as head bandage seen from the inner side.

Fig. 2 is a cross section of Fig. 1.

Fig. 3 shows a water bag as cuff-shaped bandage in elevation.

Fig. 4 is a cross section of Fig. 3.

Figs. 5 and 6 show each in cross section another form of construction of the water bag.

The water bag *a* shown in Fig. 1 is made of soft and extensible material impermeable to water, for instance rubber, and it may be in any suitable shape, in accordance with the part of the body on which it has to be applied. It may for instance have the form of a head bandage, of an abdominal bandage and the like. As rubber expands when the water is being filled into the bag, it is not necessary to give to the bag a curved shape, the bag consisting simply of two flat rubber pieces *b* and *c* connected at the edges so that a free space is formed between the two rubber pieces. A hose *d* taps into the outer wall *c*, said hose being connected to a water bag *e* of rubber or to a water ball so that water from this bag or ball *e* can be forced into the hollow space of the water bag *a*. In the connecting hose *d* a shutting off element *f* is inserted.

The water bag or ball *e* has a filling hole closed by a screw stopper.

The water is forced from the water bag or ball *e* into the waterbag *a*, after the latter has been attached on the body, by compressing said water bag or ball.

The water bag *a* has the tendency to assume, owing to the water forced in, the form of a tube of circular cross section. In this form it would touch the surface of the body only along a line or on a narrow surface, and have very little effect.

The inner wall of the water bag *a* is therefore fixed on the outer wall *c* along the edge by glueing so that a not expandible frame is formed which might further be stiffened by means of strips *g* of strong, not extensible material. The frame prevents that the inner wall *b* rolls up on the surface of the body so

that it remains in the stretched state, only the outer wall *c* bulging out.

In order to ensure a good exchanging of heat the inner wall *b* of the water bag is of thinner material than the outer wall. To the stiffening strips *f* straps *h* are attached for attaching the water bag on the body. The inner wall *b* of the water bag might be made instead of rubber of a very thin not extensible fabric. Instead of a stiffening frame *g* a stiffening cover might be provided extending over the whole wall *b*. The application of the apparatus is very easy as it can be applied like an ordinary bandage. The water can be forced into the apparatus *a* without any difficulty from the rubber bag *a* and withdrawn quite so easily.

The shape of the waterbag *a* is selected in accordance with the shape of the part of the body on which it has to be applied.

Figs. 3 and 4 show for example a poultice bag for the treatment of the arm or the leg or for the treatment of the penis. For these purposes the water bag consists of a double walled cuff *m* with two cylindrical walls *i* and *k*. In the outer wall *k* taps the hose *m*. The inner wall is of thinner material than the outer wall for better exchanging of heat. A water bag of cylindrical form does not require a stiffening frame as it is designed to be applied or placed on round or cylindrical parts of the body and that consequently the inner wall bearing against the part of the body cannot roll up. In the apparatus of this form of construction either both walls or only the inner wall alone are made of rubber. As the inner wall is bulged out by the water filled into the apparatus, a good application on the part of the body is ensured even if the cuff-shaped water bag is of a smaller inner diameter than that of the part of the body to be treated. One and the same cuff shaped water bag may be used for instance for treatment of the wrist or of single fingers. In order to make the water act directly upon the part of the body to be treated, as is the case with the commonly used poultices, the inner surface of the water bag has a cover *o* of water absorbing material, as shown in Fig. 5. This cover is attached, in any suitable manner, to the edge stiffening *q* only at the edges. The cover is dipped into water prior to the application of the apparatus. The cold or heat of the water forced into the apparatus is transmitted through the rubber wall *d* upon the water containing cover *o* and keeps this cover or the water in the same cold or warm.

A compress *g* is preferably removably attached to the apparatus.

With this object in view a flap *g* is provided, as shown in Fig. 6, on the edge of the stiffening frame *g* so that a continuous groove is formed designed to receive the cover.

Several compresses, for instance two, *o*,

and *o*, may be inserted to make the compress thicker. If no water is forced into the apparatus it may be used like an ordinary compress.

I claim:—

1. An apparatus for the external treatment of parts of the body by water, comprising in combination a poultice-bag, consisting of yieldable material impermeable to water, a water bag or ball connected to said poultice-bag, means for attaching said poultice-bag onto the part of the body to be treated, a rubber hose connecting said waterbag to said poultice bag and a shutting off element in said rubber hose.

2. An apparatus as specified in claim 1, in which the inner wall of the poultice-bag is made of extensible material.

3. An apparatus as specified in claim 1, in which the inner wall of the poultice bag is thinner than the outer wall of the same.

4. An apparatus as specified in claim 1, in which the inner wall of the poultice-bag is stiffened on the edges.

5. An apparatus as specified in claim 1, comprising in combination with the poulticebag, an absorbing compress on the outer surface of the inner wall of said poultice-bag.

6. An apparatus as claimed in claim 1, comprising in combination with the poulticebag, a stiffening strip along the edges of the inner wall of said bag, and a hose flap of this stiffening forming a groove designed to hold an absorbing compress.

In testimony whereof I affix my signature.

DAVID SARASON.
